CLAIM

The ornamental design for a cleaning pad for cleaning implement as shown and described.

DESCRIPTION

FIG. 1 is a top, front, left perspective view of the claimed design for a cleaning pad for cleaning implement.

FIG. 2 is a top view thereof;

FIG. 3 is a bottom view thereof;

FIG. 4 is a right side view thereof;

FIG. 5 is a left side view thereof;

FIG. 6 is a front view thereof;

FIG. 7 is a rear view thereof;

FIG. 8 is a bottom, rear, left perspective view thereof; and, FIG. 9 is a top, front, left perspective view thereof with example environment.

The even-length broken lines showing the remainder of the cleaning pad for cleaning implement depict environmental structure and form no part of the claimed design.

1 Claim, 9 Drawing Sheets
